UNITED STATES PATENT OFFICE.

CHARLES A. BABCOCK, OF BUFFALO, NEW YORK, ASSIGNOR TO PRATT & LETCHWORTH, OF SAME PLACE.

DESIGN FOR A CARRIAGE-STEP.

SPECIFICATION forming part of Design No. 15,757, dated February 3, 1885.

Application filed December 31, 1884. Term of patent 7 years.

To all whom it may concern:

Be it known that I, CHARLES A. BABCOCK, a citizen of the United States, residing at the city of Buffalo, in the county of Erie and 5 State of New York, have invented and produced a new and original Design for Carriage-Steps, of which the following is a specification.

This design relates to the ornamentation of the upper surface of a carriage-step by means 10 of ornamental ribs; and it consists of the special features which will be hereinafter described and claimed, and which are represented in the accompanying drawing, which represents a top plan view of the carriage-step.

15 A represents the plate of the carriage-step, which is square or rectangular in form and provided with rounded corners.

a is a marginal rib extending along the four sides of the plate A. The latter is provided 20 within the marginal rib a with four large lozenge-shaped ornaments, B, extending from the center of the plate to the four corners

thereof, and four small lozenge-shaped ornaments, C, between the large ornaments B and extending to the sides of the plates A. The 25 ornaments B are each provided with two intersecting bars, d d. All of these ornaments are outlined by raised ribs or bars on the upper surface of the step-plate.

e are openings in the plate A between the 30 ribs of the ornaments.

I claim—

The design for a carriage-step, consisting of a marginal rib, a, and lozenge-shaped ornaments B C, substantially as shown and described.

Witness my hand this 19th day of November, 1884.

CHAS. A. BABCOCK.
